CARD TRAY

Ralph R. Russell, Leicester, Mass.

Application January 6, 1950, Serial No. 7,044

Term of patent 3½ years

(Cl. D34—13)

To all whom it may concern:

Be it known that I, Ralph R. Russell, a citizen of the United States, residing at Leicester, in the county of Worcester and State of Massachusetts, have invented a new, original, and ornamental Design for a Card Tray, of which the following is a specification, reference being had to the accompanying drawing, forming part thereof.

Fig. 1 is a plan view of a card tray, showing my new design;

Fig. 2 is a side elevation thereof;

Fig. 3 is an end elevation thereof; and

Fig. 4 is a sectional side elevation, taken along the line 4—4 in Fig. 1.

I claim:

The ornamental design for a card tray, as shown.

RALPH R. RUSSELL.
